NEEDLE

Alonzo H. Little, Los Angeles, Calif., assignor of
three-fifths to Glenn O. Fowler, Los Angeles,
Calif.

Application September 1, 1937, Serial No. 161,935

5 Claims. (Cl. 223—102)

This invention relates to a needle and, more particularly, to a needle which is provided with an improved threading attachment and with a means for severing the thread or cord whenever a sewing operation has been completed.

Among the objects of the invention are: to provide an improved dog for guarding the entrance to the eye of the needle; to provide the needle adjacent to its eye with an improved shoulder construction or guide means which will open a clear path through the garment for the thread as it follows the needle, and to combine the aforementioned dog with a cutting shoulder on the needle in order that a conveniently operable means for cutting the thread will result.

A still further object of the invention is to provide a sturdy, strong, and dependable needle construction of the kind to which the invention pertains, wherein the dog which guards the entrance to the eye of the needle will also serve as a reinforcement to the portion of the needle adjacent to the entrance to its eye.

While the needle provided by this invention is more particularly intended for use as a large needle for sewing burlap and other coarse fabrics, yet it may be used to advantage in other situations.

The needle provided by this invention does away with the necessity of using a marline-spike and provides an improvement thereover, because, with this needle, the strand is pulled through the rope in the splicing operation along with the needle, whereas with a marline-spike, after an aperture has been made transversely through the rope and the pointed portion of the spike removed from said opening, the apertured portion thus created is apt to collapse and close the aperture before it can be utilized for the intended splicing purpose.

Other objects, advantages, and features of invention will hereinafter appear.

Referring to the accompanying drawing which illustrates what is at present deemed to be a preferred embodiment of the invention,

Fig. 1 is a side elevation of a needle showing the dog, which guards the entrance to the eye, in its open position.

Fig. 2 is a like side elevation of the needle except that the dog is shown in its closed position and part of the needle is broken away in order to contract the view.

Fig. 3 is an elevation of the portion of the needle shown in Fig. 2 looking thereat from the left side.

Fig. 4 is an elevation of the portion of the

needle shown in Fig. 2 looking thereat from the right side.

Fig. 5 is an enlarged cross section of the shank and dog of the needle taken on line 5—5 of Fig. 1.

Fig. 6 is an enlarged plan view of the needle structure shown in Fig. 2.

Referring in detail to the drawing, the needle therein shown comprises a body portion 5 which is of a cylindrical character except that it is tapered at one end to a point in the usual manner. Opposite to its pointed end, said body 5 is furnished with a flattened shank portion 6 which is reduced in both its cross sectional dimensions, but one side of which alines with what may be termed the back of the needle, as well shown in Fig. 1. At its outer end, said shank is furnished with a neck 7 that carries the head 8 of the needle. Like the shank 6, its neck 7 and the head 8 are flattened to a uniform thickness.

Transversely through this flattened portion of the needle extends an eye 9, said eye being elongated in the direction of the needle's length and being bounded on one side by said neck 7 and on its opposite side by a hook portion 10 with which the head 8 is provided. Said hook portion 10 terminates in a spaced relation to a shoulder 11 located at the inner side of the juncture of the shank 6 and the neck 7. This construction provides an opening or inlet passage 12 for threading the thread or strand of rope into the eye of the needle by moving the thread in a sidewise manner instead of projecting it through the eye of the needle in an endwise manner.

With the eyeleted portion of the needle cooperates a dog 15, said dog being of a generally cylindrical shape but being provided longitudinally with a deep groove or slot 16 which opens out at its inner side, said groove being of a sufficient width to permit the dog to pass with a working fit astride the flattened shank portion 6 of the needle. At the base of the needle shank 6, said dog is provided with a pair of spaced rounded ears 17, said ears passing astride the base portion of the shank 6 and cooperating with a pivot 18 to swingably secure the dog to the needle. The adjacent body portion of the needle is furnished at each side with a concave shoulder 19 which is so shaped and positioned as to limit the outward swing of the dog, stopping its opening movement at substantially the position shown in Fig. 1. A lug 20 results between said shoulders, through which the pivot of the dog extends.

The free end of the dog 15 is so positioned that, when the dog is closed, said end thereof is directed away from the pointed end of the needle and

comes substantially into contact with the adjacent end portion of the hook 10, and the outer side portion of the dog alines with the outer side of said hook portion, thus providing a continuously smooth surface around all sides of the needle which will not interfere with the passage of the needle through the garment or other work being sewed or spliced and will at the same time make a free path for the thread or cord. This smooth surface around the needle results from the fact that the cross-sectional shape of the dog includes a convexity which corresponds in curvature to the circumferential curvature of the adjacent portion of the needle. This construction also causes the dog, when closed, to form a reinforcing abutment at the extremity of the hook member 10 enabling the needle safely to resist heavy pressure applied to its eyeleted end. Owing to the fact that, when the dog is closed, its free end is directed away from the pointed end of the needle, the movements of the needle thru the work tend to keep the dog in the closed position.

It will be observed that, at each side of its grooved portion, the dog 15 has a sharp edge as viewed in cross section. These sharp edge portions of the dog pass close to each side of the needle shank 6 as the dog is swung to its closed position. As shown in Fig. 5 one edge or side of the shank 6 is beveled at 21, thus providing a knife-edge or angular shoulder 22 along one side of said shank. The adjacent sharp-edged portion of the dog cooperates with this knife edge, and thus forms a cutting means for severing by a shearing action the thread or twine carried by the needle, at the close of a sewing operation.

The stop shoulder 23 prevents the knife edge of the shank 6 from being blunted by contacting with the base of the slot 16.

40 It should be understood that the present disclosure is for the purpose of illustration only and that this invention includes all modifications and equivalents which fall within the scope of the subject matter claimed.

45 What is claimed is:—

1. A needle of the kind described having through it an eye which is furnished with an entrance opening and with a dog pivoted to swing to and from a position for closing said entrance opening, said needle having a shouldered portion

adjacent to said eye and said dog having a sharp edge portion positioned to cooperate with said shouldered portion of the needle to sever the thread after a sewing operation.

2. A needle of the kind described having through it an eye which is furnished with an entrance opening and with a dog pivoted to swing to and from a position for closing said entrance opening, said needle having a shank provided with a flattened portion adjacent to said eye 10 and said dog having a longitudinally grooved portion fittable over said flattened portion, said dog having also a sharp edge portion at at least one side of its groove to cooperate with said shank to provide a thread cutting means. 15

3. A needle having a pointed work penetrating body portion which is substantially circular in cross section, one end of said body portion being continued as a shank, neck and head all of which are flattened, said head and neck portion having an eye extending transversely through it, said eye being elongated lengthwise of the needle and being bounded on one side by said neck and on its opposite side by a hook with which said head is furnished, thus providing an inlet passage for 25 said eye, and a dog pivotally secured to the needle adjacent to the juncture of the shank and body of the needle, said dog having a cross-sectional shape which includes a convexity corresponding in curvature to the adjacent portion of the needle, and having also a longitudinal groove to fit over 30 said shank when the dog is swung to its closed position wherein it closes the entrance to said eye and forms with said shank a continuation 35 of the cross-sectional shape of the body portion of the needle throughout the extent of said dog whereby to provide a passage-making means thru the work in advance of the thread occupying said eye, the free end portion of said dog, when closed, being directed away from the point of the needle. 40

4. A needle having an eye provided with an inlet, and with a shank having an angular shoulder providing a knife edge adjacent to said inlet, and a dog positioned to open and close said inlet, said dog having an edge positioned to move across 45 the angle of said shoulder with a shearing action.

5. The subject matter of claim 4 and, said shank having a stop shoulder adjacent said knife edge, limiting the closing movement of said dog.
